UNITED STATES PATENT OFFICE.

CHARLES H. WILD, OF BALTIMORE, MARYLAND, ASSIGNOR TO BURT MACHINE COMPANY, INCORPORATED, A CORPORATION OF MARYLAND.

CAN-LABELING-MACHINE PICK-UP CEMENT HEATER.

Application filed July 18, 1924. Serial No. 726,889.

In the operation of labeling cans, which in every cannery of any considerable capacity is performed by special automatic machines known as labeling machines through which 5 the cans are rolled on ways, picking up the labels as they go, the cans are first spotted with cement or glue and then passed over the label pack, the spot of cement or glue on each can causing it to pick up a 10 label as it passes, each label being thus rolled about the corresponding can and finally secured by pasting the lap end.

The glue or cement, known in the trade as pick-up glue, by means of which the 15 cans are spotted to enable them to pick up the labels, is at normal temperatures solid or semi-solid, and is kept hot in a suitable receptacle in the machine during the entire 20 operation of the machine, each machine being provided with heating means for this purpose.

The cement or glue which is used in this way comes in large cans holding several 25 gallons which when cold is a solid or semi-solid hard or sticky mass of the consistency of resin or pitch, and must be dug or broken from the cans. This results in waste from failure to empty the cans. If an operator forgets to fill the glue pot in connection 30 with his machine, and the glue or cement is permitted to run out, it is necessary to dis- 35 continue the operation of the machine until a new supply can be heated in the glue pot, the heating capacity of which is not ordi- 40 narily sufficient to perform this operation quickly, the heating apparatus in the glue pot being rather intended to maintain the glue in liquid condition than to melt hard cement, so that a delay results.

The object of the present invention is to 45 provide an apparatus by means of which the cans of pick-up glue may be heated and emptied without loss, the apparatus including a chamber in which the cans are heated and means for heating them directly 50 and a receptacle at the bottom of the heated chamber which holds and maintains continually a supply of liquid glue or cement, and has means for heating the liquid glue to keep it in liquid condition, the apparatus includ- 55 ing a drain cock or tap with a valve mainly

inside the receptacle which is thus kept hot, preventing hardening of the glue in the tap so that the glue or cement flows freely at 55 all times.

The cans of cement are opened at the top and placed in inverted position inside the enclosure or chamber and in the immediate vicinity of a heating unit, which at the time of starting, i. e., when the first can of glue 60 is heated, is supplied with heat sufficient to liquefy the material. The heating chamber is completely closed as to the bottom portion, which serves as a receptacle for the liquid cement, and is also provided with a heating 65 unit at the bottom, which is submerged in the liquefied material, keeping it heated to the point of liquefaction.

While it is deemed necessary to apply heat 70 directly, by means of a heat unit in the im- mediate vicinity of the can, to the first can which is placed in the heater at the begin- 75 ning of operations, the heat radiated from the liquid material which is maintained at a temperature above the temperature of liquefaction by the submerged heating units, is sufficient to melt the contents of the cans, subsequently inserted, except when the ma- 80 terial in the heater or oven becomes wholly or almost wholly exhausted, as in instances 85 of negligence and oversight on the part of the attendant.

By means of this apparatus I remove the 85 glue or cement from the cans and provide a continuous supply of liquid cement always 90 ready to replace that in the cement or glue pots on the machines, thus overcoming the difficulties previously encountered.

In the accompanying drawing I have il- 95 lustrated a can label pick-up glue heater in accordance with my invention.

In the drawings—

Figure 1 is a front elevation of the ap- 95 paratus in the preferred form.

Figure 2 is a horizontal section of the same 95 on the line 2, 2 of Figure 1.

Figure 3 is a vertical section parallel to the plane of Figure 1 and on the line 3, 3 of Figure 2.

Figure 4 is a horizontal section on the line 100 4, 4 of Figure 1.

Figure 5 is a front elevation of a slightly

different form of apparatus having two heating units instead of one in the immediate vicinity of the can being treated.

Figure 6 is a fragmentary enlarged vertical section on the line 6, 6 of Figure 2 looking to the left in said Figure.

Figure 7 is a plan of the electrical circuit employed in heating the apparatus shown in Figures 1 to 4 inclusive.

10 Figure 8 is a plan of the electric heating circuit employed in the apparatus, Figures 5 and 6, both said forms of the invention being electrically heated.

15 Figure 9 is an elevation of the upper portion of the apparatus showing a steam heating coil in place of the electric heating element which heats the cans containing the cement, i. e., the upper heater.

20 Figure 10 is a horizontal section showing the lower heating element where steam heating is employed.

Figure 11 is a section on the line 11, 11, Figure 9, showing the upper heating element in the steam heated device in plan.

25 Referring to the drawings by numerals, each of which is used to indicate the same or similar parts in the different figures, the apparatus, as shown, consists of an upright structure in the nature of a cabinet 1 comprising a chamber or oven 2 consisting of outer walls 3 of wood, terminating below in legs or supports 41, so that the casing or chamber is placed a foot or more above the floor, and inner walls 4 of sheet metal preferably spaced inwardly from the outer walls to provide an interwall air or vacuum space 5, the interwall members being supported on suitable struts 6.

40 The chamber or oven 2, as shown, is of elongated rectangular shape about twice as high as it is wide and having a door opening 7 in the upper half, closed by a door 8. Below the door the chamber is completely closed at the sides forming a container for 45 the melted or liquid cement, as hereinafter described.

45 In Figures 3 and 4 I have shown just below the level of the door opening 7, transverse horizontal supports in the nature of straps 9 spaced apart less than the width of the cement cans to be treated. These extend from one side to the other of the chamber and are turned at right angles as to the ends 10, which ends 10 are secured to the 55 walls by rivets or bolts 11 passing through these ends, and the sheet material 4 forming the inner walls.

I have also shown a transverse support 13 at the rear in the nature of an angle having 60 an upwardly projecting flange 14 serving as positioning means for the cans.

At the bottom of the receptacle I have shown a drip cock or spigot 16 in any suitable form, the same being controlled by a 65 valve which may be a plug valve or gate

valve having a stem 17 and handwheel or other suitable control. The drip cock, as shown, includes an elbow 18 connected to the T valve casing 19, the other end of the valve casing being open at 20, and the valve packing box 21 extending outward through the metal walls 4 and having one nut 22 on the inside of the wall, and a second nut 23 on the outside of the wall whereby the valve chamber or casing is held in position by tightening the nuts. The elbow 18 is connected to a short section of pipe 24 which extends downward through the bottom of the oven or cabinet and may be suitably held by means of nuts 25 and 26. In this connection it is important to note that the drip cock and valve, except for the projecting end 24, are entirely within the heated receptacle and are thus kept free for the flow of the melted cement or glue, the constant temperature above the melting point of the material thus maintained preventing hardening of the glue in the passage, and consequent obstruction of the passage.

70 The cans of cement or glue being first opened at the top, are inverted and placed in the oven or heater in inverted position with the open top edges of the can resting on the supports 9, 13, see Figure 3, and when the contents of the cans is heated by means of the can heating unit 28, shown in the form of a heating member which is semi-circular in plan, and which in the form shown in Figure 3 is heated by means of an electric coil illustrated diagrammatically in Figure 7 and to be hereinafter described.

75 It is at present regarded as necessary to energize the heating unit 28 only when the temperature of the heater or oven 2 is down on account of the apparatus having been out of operation or the supply of glue having been exhausted, an immediate supply is necessary, and, further, on account of the absence of a supply of melted glue, the apparatus has comparatively little stored heat or heat units to be imparted to the glue in the can which is being placed in the chamber to be melted as aforesaid.

80 In Figure 5 I have shown an apparatus similar to that illustrated in Figure 3 except that it is supplied with two semi-circular can heating units 29 and 31, one over the other, and substantially parallel and intended to be in close heat-imparting relation with the can to be heated during the 85 operation of the heater. This gives a variable heating capacity to this portion of the apparatus, the coils contained in the said heating units being capable of separate operation as illustrated in the diagram, Figure 8.

85 In Figures 2, 3 and 6 I have shown in addition to the can heating units 28, or 29, and 31, intended to be in direct contact with the can, other heating units 33 and 34, en-

closed within straight horizontal pipes 35 extending substantially across the bottom of the heating chamber or oven 2, the lower portion of the chamber below the door 8 referred to, which is liquid tight, being known as the liquid glue or cement receptacle 36. These pipes 35 enclose the heating units 33, 34, each comprising in this instance an electric coil illustrated diagrammatically in Figures 7 and 8, and to be later described, extend at their rear ends into the immediate vicinity of the drain cock or plug valve 16, and at their opposite ends 37 they are open and protrude from the casing or cabinet 1. In the operation of the oven or cement heating apparatus, these heating units are continuously or almost continuously energized, serving to maintain the liquefied cement at a temperature above the point of liquefaction and to keep the drip cock at a corresponding temperature so that the liquid cement may be easily and conveniently drawn off as required into a small receptacle as indicated by reference character 38 in Figure 1, to be transported to and placed in the glue or cement pot of the labeling machine or machines.

In Figures 9, 10 and 11 I have shown steam heating coils 42 and 43, the coil 42 being substituted for the lower heating units 33, 34, and the coil 43 for the can heating unit 28 or the can heating units 29 and 31. These may be arranged in any suitable manner. The coil 42 as shown is U-shaped having two parallel horizontal legs connected together by the cross-arm of the U and one of said legs being connected by a pipe 44 to a steam main 45. There is a valve 46 controlling the pipe 44 leading to the coil 42 and a radiator trap 47 to drain the coil of condensed water.

The coil 43, as shown in Figure 11, is semi-circular in plan to partially encircle or enclose the cans. This coil in the form shown, as seen in elevation in Figure 9, has two legs 50, 51, i. e., is double or U-shaped, the upper leg being connected to the steam main 45 by a pipe 52 and having therein a valve 53. The coil is drained by a trap 54 connected to the lower leg of the coil 51.

In Figure 7 I have shown a circuit plan of the electric heating apparatus in Figures 1, 2, 3, 4 and 6, and in Figure 8 I have shown a circuit plan of the heating apparatus in Figure 5.

The diagram Figure 7 includes positive and negative mains 56 and 55, the heating units 33 and 34 for the liquid cement or glue receptacle shown in Figure 3 submerged in the liquid near the bottom, containing electric coils 58 and 59 connected in series across the mains 55 and 56 by way of a switch 60 of any preferred type. The diagram also includes a heating unit 28 corresponding to the semicircular can heating

member 28 of Figure 4 containing a heating coil 61 connected across the mains 55 and 56, and having in one said connection a switch 62 for throwing the coil into and out of circuit independently of the coils 58 and 59.

The diagram of Figure 8 which applies particularly to the form of apparatus illustrated in Figure 5, shows two heating units 33, 34 corresponding exactly to those described in Figure 7, under the same reference numerals, except as to the manner of connecting the electrical circuit and containing coils 58 and 59. These coils are connected in series across the plus and minus mains 65 and 66. This connection comprises a conductor 67 connecting the corresponding terminals of the two coils 58 and 59, the conductor 68 and 68' connecting the other terminal of the coil 59 to the plus main 65 and a conductor 69 connecting the other terminal of the coil 58 to the minus main 66. The circuit includes a two-point switch 70, the swinging arm or blade of which, 71, is connected to the main 65, by conductor 68, one of the switch contacts 72 being connected to the coil 59 by the conductor 68' and the other switch contact 73 being in the connection 67. By placing the switch arm or blade 71 in contact with the terminal 73, the coil 59 is cut out of circuit, and by placing it in contact with the terminal 72, the coils 58 and 59 are connected in series. The conductor 69 which connects the coil 58 to the main 66 contains a three-point switch 75 having the swinging arm 76 thereof connected by one portion of the conductor 69 to the coil 58. One terminal of this switch marked "High" is connected by the other portion of the conductor 69 to the minus main 66, and the three contact points of the switch marked "High", "Medium" and "Low" are connected together by a resistance 77, 78.

In the operation of this portion of the circuit it is apparent that the coil 59, which it will be understood is in the heating unit 34, which is one of the units 33, 34 at the bottom of the liquid glue or cement receptacle, may be cut out at will by throwing the switch arm 71 in contact with the terminal 73. These coils are cut in and out depending upon the amount of heat desired at the bottom of the liquid cement receptacle.

The heat in these coils may be further varied or entirely cut out by means of the switch 75. When the switch arm 76 is in contact with the high terminal, and both of the coils 58, 59 are in circuit, the switch arm 71 being on the contact point 72, the maximum heating effect is obtained, and this heating effect is reduced without cutting out the extra coil 59 by moving the switch arm 76 into contact with the medium point or the low point as may be found

desirable, and three other heating effects are obtained by use of these three points, "High," "Medium" and "Low," with the single coil 58, the coil 59 being cut out as 5 already described.

The diagram, Figure 8, corresponding to Figure 5, also includes the two heating units 29 and 31 containing coils 80 and 81, which as shown are connected together in parallel 10 across the mains 65 and 66 by conductors 81 and 82, and conductors 83 and 84 which connect the respective ends of the coils together. The conductor 81 contains a three-point switch 85 having "High," "Low" and "Medium" terminals so marked and an off-terminal also marked with the word "Off," the high, low and medium terminals being connected by a resistance 86 and 87. The swinging arm 88 of the switch is connected 20 to one portion of the conductor 81 and the high terminal is connected to the other portion of this conductor. By moving the switch arm 88 from one terminal to the other, cutting the resistance in or out, a 25 high, low or medium heating effect is obtained with the two coils in circuit. The conductor 84 which connects two corresponding ends of the coils 80 and 81 contains a single point switch 89 between the junction 30 of the conductors 82 and 84, and the end of the coil 80 whereby the coil 80 may be cut out, so that with the switch 81 and switch 85, three more heating effects are obtained.

The operation of the device has been quite 35 fully discussed in the preamble and in connection with the description of the apparatus.

In accordance with the operation of the present device the cement cans are opened 40 at the top and placed in the heater in inverted position on the rack 9, 13. The operation of the apparatus is intended to be continuous with the operation of the corresponding labeling machines, of which one such heater will serve one, two or several 45 machines.

In starting when the machine and glue 50 are cold, the upper heating units 28 or 29, 31 or 50, 51, in accordance with the construction of the particular machine, are then placed in full operation, and as soon as the cement begins to flow, the lower heating units 33, 34 are also energized, so as to maintain the cement which accumulates in 55 the bottom of the heating chamber, as shown at 93 in Figure 3, in a liquid or fluid condition. When the can of cement is emptied into a receptacle, the upper heating units are shut off and the can may be removed. 60 When the liquid in the bottom of the receptacle is drawn down below a certain predetermined point a new can is inserted, similarly opened at the top and inverted and the operation continued. When the ap-

paratus is fully heated and contains a considerable amount of heated cement at the bottom, the can-heating units at the top of the chamber are generally found unnecessary, sufficient heat to melt the cement being obtained from the lower heating units and 70 the heated liquid, but in starting after a shut-down, as in the morning, and when the cement is nearly exhausted from the bottom of the chamber, the can heating units are deemed necessary and are placed in operation to heat the cement in the cans. 75

Whenever the cement or glue pot on one of the labeling machines is nearly exhausted or emptied of liquid cement, a conveniently portable receptacle 38, see Figure 1, is 80 placed beneath the drip cock or the outlet 24 thereof, and the valve 16 is opened to release a quantity of liquid cement which is then carried in the receptacle to the machine and 85 poured into the glue pot of such machine.

In this way all the difficulties previously 90 incident and regarded as essential to maintaining a supply of glue or cement in the pick-up or spotting apparatus of the machines, are overcome and avoided. 95

It is apparent from the diagrams Figures 7 and 8, and from the illustration of the steam apparatus, that the can heating units and the liquid heating units may be varied as to the degree of heat transmitted thereby, 100 to suit the exact convenience of the operator, and that in all instances the coils may be independently operated, so that either the upper or lower units or portions thereof may be separately heated to varying degrees of 105 intensity, giving exactly the desired heating effect and avoiding burning of the cement and waste of heat.

I have thus described specifically and in detail an apparatus embodying my invention 110 in various forms in order that the nature and operation of the same may be clearly understood; however, the specific terms herein are used descriptively rather than in a limiting sense, the scope of the invention 115 being defined in the claims.

What I claim and desire to secure by Letters Patent is:

1. In an apparatus for heating pick-up cement for can-labeling machines, a heating chamber having means for holding the cement cans in inverted position, heating means adjacent the cans as thus held, and heating means near the bottom of the chamber, the receptacle having an opening to admit the cans, and a closed portion below said opening to hold liquid cement from the cans, and means for separately controlling the heating effect in said respective heating means. 120

2. In an apparatus for heating pick-up cement for can-labeling machines, a heating chamber having means for holding cement

cans in inverted position, heating means adjacent the cans as thus held, and heating means near the bottom of the chamber, the chamber having an opening at the side to admit the cans, and a closed portion below said opening to hold liquid cement from the cans, and means for separately controlling the heating effect in said respective heating means, and varying the heating effect as applied to the cans and to the liquid cement 10 separately and independently.

Signed by me at Baltimore, Maryland,
this 16th day of July, 1924.

CHARLES H. WILD.
